UNITED STATES PATENT OFFICE.

FREDERICK AUGUSTUS EDWARDES, OF LONDON, ENGLAND.

APPARATUS FOR USE IN TREATING METALLIC ORES.

SPECIFICATION forming part of Letters Patent No. 624,633, dated May 9, 1899.

Application filed July 2, 1898. Serial No. 685,037. (No model.)

To all whom it may concern:

Be it known that I, FREDERICK AUGUSTUS EDWARDES, a subject of the Queen of Great Britain, residing at London, England, have 5 invented new and useful Improvements in Apparatus for Use in the Treatment of Metallic Ores, (for which I have applied for a patent in Great Britain, No. 11,011, dated May 14, 1898,) of which the following is a specification.

10 My invention relates to apparatus for use in the process of treating ores for the recovery of metals or metalloids therefrom wherein dichlorid or chlorid of sulfur or impure nitrates are used in combination with sodium chlorid or other well-known solvent. In treating sulfid ores by this process the liberated sulfur has to be removed, and this is usually effected by skimming. This skimming, however, is a difficult operation, owing to the fact that 20 the sulfur is kept in a constant state of circulation with the heated liquid and is generally mixed more or less with the gangue at the bottom of the vat.

The object of my invention is to simplify 25 this process of skimming and to effect it more thoroughly than heretofore; and to this end it consists in the construction and application of a skimming apparatus which collects the sulfur directly it rises to the surface of the 30 liquid in the vat, but retains it in the liquid until the process is completed, the said skimming apparatus being attached to the stirrer usually employed.

To enable my invention to be fully understood, I will describe the same by reference to the accompanying drawings, in which—

Figure 1 is a sectional side elevation of apparatus provided with my improvements, and Fig. 2 is a sectional front elevation of the 40 same. Fig. 3 is a section on the line 3 3, Fig. 1.

45 *a* is a framing carrying the apparatus, and *b* is a vat made of wood or other material which is not injured by the substances employed, the said vat being mounted upon the beam *c*, provided at the ends with trunnions *d d*, carried in bearings in the frame *a* in such a manner that the vat can be tilted. At the center of the said vat is formed a tubular portion *e*, through which a shaft *f*, which carries 50 an agitator or stirrer *g*, extends, the said tubular portion *e* forming one wall of an annu-

lar space, in which the arms *h h* of the agitator travel around. The said arms *h h* project downward from the top cross-bars of the 55 agitator and carry at their lower ends the stirring-boards *i i*. This agitator *g*, with its arms and boards *i i*, and also the upper end of the shaft *f* and the cap or cover *j* of the tubular portion *e* are made of wood or other material 60 which is unaffected by the materials used in treating ores. At the lower part of the annular space in the vat is arranged filtering material *k*, above which is placed a perforated false bottom *l*, through which the liquid can 65 percolate as it is drawn off through a cock *m*.

To permit of removing from the vat the gangue or solid matter remaining after the treatment is completed, I provide a door *n*, which is normally held in place by a screw *o* 70 in a bridge-piece *p*, which can be removed when the door *n* is removed. When the vat is tipped upon its trunnions, it will be obvious that the material in the vat can be readily removed or washed through the opening. 75

q q are jacks or appliances which serve for tipping the vat in either direction and for holding it steady during the operation of the apparatus.

r is a pinion mounted upon the driving-shaft *s* and engaging with a wheel *r'* upon the shaft *f*, the said pinion being made free to slide upon the said shaft, so that it can be drawn back, so as not to prevent the tipping movement of the vat. 80

The apparatus thus far described forms no part of my invention, the description being given in order to show a complete apparatus provided with my improvements.

t t are my skimmers, which are formed of 90 open-work—such, for instance, as plaited or woven cane or hair—which will not be injured by the liquid. These skimmers, as shown, are attached to the arms *h h* of the stirrer in such a position that they are partly immersed in 95 the liquid, their hollow or open sides facing the direction in which they move, so that any sulfur which rises to the surface of the liquid will be caught by the said skimmers and be prevented from escaping therefrom by the pressure of the liquid as the stirrer rotates. As shown, these stirrers are only of about half the width of the annular space of the vat, the skimmers on alternate arms being arranged 100

to skim from different portions of the surface. It is to be understood, however, that the said skimmers may extend to a greater or less extent along the arms and may be of any desirable shape or construction.

5 *u* is a cover which is adapted to close the top of the vat, the said cover being jointed upon the edge of the vat by means of a ring *v*, of india-rubber or other suitable material, upon which the cover lies. In practice the weight of the cover will generally be sufficient to compress the india-rubber to a sufficient extent to secure a tight joint. Should this, however, not be the case, the cover can 15 be weighted, or clips or other suitable devices may be provided for producing the desired compression. The said cover has connected to it a rope or chain *w*, passing over pulleys on the frame *a* and which serves for 20 lifting the cover when required.

x x are cocks placed upon the cover and which serve for drawing off from time to time the gases which are given off during the treatment of the ore, the said cocks being adapted 25 to have pipes connected to them in order to convey the gases to a storage-chamber or the like.

y is a funnel or filling-tube which is fixed to the side of the vat and opens into the latter below the level of the bottom edge of the skimmers and through which the saturated solution and the ore to be operated upon can be introduced. *z* is a plug which normally serves to close the said funnel.

35 One of the great advantages of my invention is that by closing the vat with a cover the escape of noxious fumes is prevented.

Although I have described my invention as applied to the treatment of sulfid ores, it is to 40 be understood that it is also applicable to the treatment of what are known as "free-milling" ores or of other ores to which sulfur is added.

Having now particularly described and ascertained the nature of my said invention and in what manner the same is to be performed, I declare that what I claim is—

45 1. In apparatus for the treatment of metallic ores, the combination with a vat for con-

taining the ores, of skimmers consisting of 50 perforated receptacles, located in a horizontal plane above the bottom of the vat, and means for moving said receptacles in the vat, in a plane parallel with the surface of the liquid, said receptacles being open on the side 55 facing the direction in which they are moved through the liquid, substantially as described.

2. In apparatus for the treatment of metallic ores, the combination with a vat for containing the ores, of a revolving frame, skimmers carried by said frame, and located in a horizontal plane above the bottom of the vat, said skimmers consisting of a perforated receptacle with the side toward the direction of rotation of said frame open, and means for 60 revolving said frame and skimmers, substantially as described.

3. In apparatus for the treatment of metallic ores, the combination with a vat, of a revolving frame provided with stirrers, and a 70 series of skimmers carried by said frame, each consisting of a perforated receptacle open on the side toward the direction of rotation of the frame, and means for revolving said frame, substantially as described. 75

4. In apparatus for the treatment of metallic ores the combination with a vat having a stirrer and a skimmer working in the said vat, of a cover for hermetically closing the said vat, substantially as described. 80

5. In apparatus for the treatment of metallic ores, the combination of a vat having an annular space within it, a stirrer traveling around in the said annular space and a skimmer or skimmers attached to the said stirrer 85 and moving therewith, substantially as described.

6. In apparatus for use in the treatment of metallic ores the combination with an annular vat having a stirrer moving therein and 90 skimmers attached to and moving with the said stirrer, of means for tipping the said vat for discharging the contents, substantially as described.

FREDERICK AUGUSTUS EDWARDES.
